ABSTRACT OF THE DISCLOSURE

An orthodontic bracket for receiving and mounting an arch wire which includes an arch wire retaining pin which can be readily manipulated for retention and removal of the arch wire and which also may be arranged to be mounted integrally with the bracket whereby removal of the pin is not required for mounting and removal of the arch wire.

BACKGROUND OF THE INVENTION

This invention relates generally to an orthodontic bracket of the type used in the art of orthodontics in which a bracket is affixed to a tooth band which encircles the tooth and the bracket receives an arch wire through which corrective forces are applied to the tooth in order to effect a straightening of the tooth. Orthodontic brackets are well known in the art. However, as will be understood by those skilled in the art, the brackets and other apparatus used in orthodontics must be extremely small so as not to discomfort the patient when worn in the mouth during extended periods. Since the orthodontist is performing manipulations in the mouth of the patient, it is also desirable that the apparatus be readily operable and with the minimum number of loose parts. It is also desirable that the bracket have maximum versatility so that it may preferably perform different functions as may be required during the normal extended period of patient treatment thereby reducing the necessity for changing apparatus during treatment as corrective movement of the teeth takes place.

SUMMARY OF THE INVENTION

Generally speaking, in accordance with the invention, a bracket is formed with a rear portion which mounts the bracket to a tooth band and a forwardly extending portion having a slot or bore which receives a pin which extends from the forwardly extending portion to the rear portion to thereby define an area for receiving the arch wire. The pin is positionable for securing and permitting removal of the arch wire and the bracket may also include means for securing ligature wires to the arch wire.

With the foregoing construction, it is possible to provide an effective and yet simple bracket which can be easily manipulated to lock into position an arch wire and which can be so arranged as to minimize the area of contact between the bracket assembly and the arch wire to minimize friction to permit relative movement as corrective repositioning of a tooth takes place and to permit the orthodontist to more accurately control the directions of forces applied to the tooth.

Accordingly, it is an object of this invention to provide an improved orthodontic bracket.

Another object of this invention is to provide an improved orthodontic bracket with minimal areas of contact between the bracket and the arch wire.

A further object of the invention is to provide an improved orthodontic bracket in which the arch wire retaining means remains connected to the bracket portion during arch wire insertion or removal.

Still other objects and advantages of the invention will in part be obvious and will in part be apparent from the specification.

2

The invention accordingly comprises the features of construction, combinations of elements, and arrangement of parts which will be exemplified in the constructions hereinafter set forth, and the scope of the invention will be indicated in the claims.

BRIEF DESCRIPTION OF THE DRAWINGS

For a fuller understanding of the invention, reference is had to the following description taken in connection with the accompanying drawings, in which:

- 10 FIG. 1 is a perspective view of a preferred embodiment of an orthodontic bracket constructed in accordance with the instant invention;
15 FIG. 2 is a sectional view taken along line 2—2 of FIG. 1;
FIG. 3 is a partial sectional view taken along line 3—3 of FIG. 2;
FIG. 4 is a perspective view of an alternate embodiment of the instant invention;
20 FIG. 5 is a sectional view taken along line 5—5 of FIG. 4;
FIG. 6 is a top plan view of another embodiment of the instant invention;
FIG. 7 is a perspective view of a tool useful for manipulating, in the patients mouth, the pin portion of a bracket constructed in accordance with the teachings of this invention;
25 FIG. 8 is a partial top plan view of the bracket of FIG. 1 with an arch wire and spring assembled therein;
30 FIG. 9 is a front elevational view of the bracket assembly shown in FIG. 8;
FIG. 10 is a sectional view taken along 10—10 of FIG. 9;
FIG. 11 is a perspective view of still another embodiment of the instant invention; and
35 FIG. 12 is a perspective view of a pin suitable for use in the FIG. 11 embodiment.

DESCRIPTION OF THE PREFERRED EMBODIMENTS

40 Referring now to FIGS. 1 through 3, a tooth band is indicated generally at 21. It will be understood that the various elements are shown at a substantially enlarged scale since the apparatus used in orthodontics is so small that it is often difficult to observe the features of construction with the naked eye. The bracket of the preferred embodiment of FIGS. 1 through 3 is indicated generally at 22 and the bracket is designed for receiving and retaining an arch wire (not shown). Bracket 22 includes rear plates 23 and 24 which are permanently secured to tooth band 21, usually by welding. Projecting forwardly from rear plates 23 and 24 is an upright 25 which terminates, at the upper edge thereof, in a knife edge 26. It is contemplated that the bracket portion shown in FIGS. 1 through 3 may be fabricated of sheet material, such as stainless steel, and thereby be formed, except for the pin as will hereafter be described, of a single sheet of material. With such construction, upright 25 would be composed of two layers secured together, such as by welding, as best seen in FIG. 3, with the knife edge being clearly indicated at 26 in FIG. 3.

45 Extending outwardly from upright 25 is a tube 27 which may also be formed from the single sheet of stainless steel as rear plates 23 and 24 and upright 25. In the embodiment of FIGS. 1 through 3, the internal surface 28 of tube 27 is threaded for receiving the pin portion of the bracket, as will now be described.

50 Pin 31 has a threaded lower end 32 mounted in tube 27. The upper end 33 is bent substantially normal to the 55 axis of the lower end.

55 Rear plates 23 and 24 define therebetween a recess for receiving the upper end of the pin. The recess is defined

by a vertical edge 34 on rear plate 24 and a sloping edge 35 on rear plate 23. As shown in FIG. 2, vertical edge 34 acts as an abutment or stop for the upper end of the pin when the pin is rotated to the closed position, which is the position shown in FIGS. 1 through 3. Sloping edge 35 also tends to retain the upper end of the pin in the closed position but, because it slopes away, it will permit the pin to ride up and deflect when it is desired to open the bracket by rotating pin 31 in the normal opening direction for a right hand thread. The assembly of pin 31 to tube 27 in the first instance may be accomplished before the upper end of the pin is fully bent to its operative position.

As shown in FIG. 2, with the pin in the closed position, an area indicated as 36 is defined for receiving an arch wire. In order to insert the arch wire in area 36 or remove it therefrom, it is only necessary to rotate pin 32 through 90° whereby the longitudinal axis of the upper end of the pin extends parallel to rear plates 23 and 24, rather than perpendicular thereto. In such position, area 36 will be fully accessible for mounting or removal of the arch wire. With the arch wire in place, the pin is rotated 90° whereby the upper end of the pin is retained between vertical edge 34 and sloping edge 35. The orthodontist may remove or replace or manipulate the arch wire as often as desired by merely rotating pin 31 and he need not be concerned with loose bracket parts. Once the pin is properly closed, it will not open inadvertently.

With the aforesaid construction, the arch wire, which is generally circular, can effect point contact with the bracket. On the bottom, it will engage knife edge 26 with the point contact resulting from tangential engagement between a line and a circle. On the front side, the circular arch wire will engage the surface of the circular pin for point contact and the same is true on the top side of the arch wire. For point contact at the rear side, the leading edges of rear plates 23 and 24 may be formed at joint 39 into a knife edge (not shown) similar to knife edge 26.

In manipulating pin 31, a tool 41 such as is shown in FIG. 7 may be especially useful. A rod 43 extends from the handle portion 42 at a 45° angle and a slot 44 is provided at the outer end of rod 43 so that during rotation of pin 31 through the 90° required to fully open and fully close arch wire receiving area 36, the tool can be manipulated to either side 45° left or right of center to minimize obstruction of the tool by the cheeks and mouth of the patient.

Referring now to FIGS. 4 and 5, an alternate construction of the bracket is shown. In the construction of FIGS. 4 and 5, the bracket is formed of a rear plate 23, rear plate 24 and upright 25 substantially as described in connection with FIGS. 1 through 3. The tube 45, while being similar to tube 27, is nonthreaded and the upper end 46 thereof is below the level of knife edge 26 as best seen in FIG. 5. A pin 47 is received in tube 45 and is provided with a headed lower end 48. The upper end 49 of pin 47 is bent with its longitudinal axis substantially normal to the longitudinal axis of the portion of the pin passing through tube 45. Pin 47 may be assembled through tube 45 before the upper end thereof is bent to position since head 45, which may be formed integrally with the pin, would prevent mounting of the pin in the tube via the head end.

Head 48 limits the upward movement of pin 47 in tube 45. A suitable collar 51 frictionally engages around pin 47 so as to limit the downward movement of the pin in the tube and thereby properly position the pin for effective operation of the bracket.

Rear plates 23 and 24 are preferably provided with the edges 35 and 34, respectively, whereby the pin will be retained in the closed position as previously described in connection with the embodiments of FIGS. 1 through 3. As shown in FIG. 5, with pin 47 in the closed position, an area indicated as 52 is defined for receiving the arch

wire. The point contact for a circular arch wire described in connection with the embodiment of FIGS. 1 through 3 holds equally with respect to the embodiment of FIGS. 4 and 5.

Note that, in FIG. 4, a pair of ligating loops 53 are shown as being formed as part of rear plates 23 and 24. The ligating loops may be including as part of any of the brackets disclosed and described in this application and the formation of the bracket from sheet material lends it easily adaptable for formation of integral ligating loops. The function performed by ligating loops and the ligature wires anchored therein are well known in the art and require no further description.

Referring to FIG. 6, a bracket 55 is shown as being formed of rear plates 56, 57 and 58, two uprights 59 and 61 and two tubes 62 and 63 respectively extending from uprights 59 and 61. Pins are not shown as mounted in the tubes for the sake of clarity. The primary difference between the FIG. 6 bracket and the brackets previously described is that two positions are provided for receiving and mounting an arch wire on a single tooth. In certain applications, such an arrangement may be especially useful and the miniaturization capable with a bracket constructed in accordance with the teachings of this invention make it possible to provide two independent mounting points for an arch wire on a single tooth. The tubes 62 and 63 may be threaded to receive a pin such as pin 31 or may be arranged to receive a pin such as pin 47 or, for that matter, any other type of pin that will perform the function of retaining an arch wire.

In FIGS. 8 through 10, there is depicted a bracket 22 of the type shown in FIGS. 1 through 3 including a threaded pin 31. The disclosure of FIGS. 8 through 10 indicates how a bracket might appear in use with an arch wire 64 mounted therein. With the bracket of the instant invention, the orthodontist can readily apply a biasing force between the bracket and the arch wire by the provision of a spring 65 which requires no additional mounting means. The spring can be formed with a loop 66 overfitting pin 31 and one end 67 of the spring may be biased into contact with a rear plate while the other end is wrapped around or engages the arch wire to provide the desired biasing force.

The bracket of the instant invention is also useful with a nonrotatable pin and, with such an arrangement, the embodiment shown in FIGS. 11 and 12 would be preferred. The bracket, preferably formed of sheet material, would include rear plates 71 and 72 welded to a tooth band 21 and an upright 73 having a knife edge 74 would extend outwardly from the rear plates and terminate at a tube 75. The cross-sectional configuration of the passage through tube 75 would depend on the cross-sectional configuration of the pin to be received therein. It would be noncircular to avoid relative rotation between the tube and the pin and it could be square, rectangular or oval. A rectangular configuration is shown in the embodiment of FIGS. 11 and 12. A pin 76 having the same general cross-sectional configuration as that of the passage through tube 75 will normally be formed as an inverted J shown in FIG. 12 so that the short leg 77 may be received in a slot 78 between rear plates 71 and 72 and the long leg 79 will be insertable through tube 75 after an arch wire has been mounted in position.

Pin 76 would be formed of a soft material such as soft stainless steel or soft brass whereby, after the pin had been properly positioned to retain an arch wire (not shown) it would be bent as indicated at 81 in FIG. 11 to retain the pin within the tube. Since the pin is of soft material, it can be easily unbent when it is desired to remove or manipulate the arch wire and the pin can be bent and unbent several times before it work hardens whereafter it can be discarded and another used in its place.

The brackets heretofore described are especially suited for coating with a tooth colored polyvinyl material which

would be especially desirable in the treatment of adults, which is increasing daily.

The embodiments disclosed herein represent only a few of the configurations of brackets, including the pins therefor, that can be developed from the principles of the instant invention. The basic concept, is the provision of plates or other means secured to the tooth band which will support a tube in spaced relation so that a pin may extend between the tube and the plates for defining an arch wire receiving area.

It will thus be seen that the objects set forth above, among those made apparent from the preceding description, are efficiently attained and, since certain changes may be made in the above constructions without departing from the spirit and scope of the invention, it is intended that all matter contained in the above description or shown in the accompanying drawings shall be interpreted as illustrative and not in a limiting sense.

What is claimed is:

1. An orthodontic bracket comprising a tube having 20 a passage therein, at least one plate for securing said bracket to a tooth band, a spacer extending between said tube and said plate and having an upper edge, and a pin moveably mounted in said passage and having a portion thereof extending toward said plate in spaced relation to said upper edge, said plate including means for retaining a portion of said pin, said pin extending through said tube and being provided with a headed lower end and a collar mounted thereon in engagement with said tube whereby said headed end and said collar retain said pin in said tube, said pin being rotatable in said tube for rotation between a position whereby said portion thereof extends toward said plate to a position whereby said portion thereof extends substantially parallel to said plate.

2. An orthodontic bracket comprising a tube having 35 a passage therein, at least one plate for securing said

5 bracket to a tooth band, a spacer extending between said tube and said plate and having an upper edge, and a pin moveably mounted in said passage and having a portion thereof extending toward said plate in spaced relation to said upper edge, said plate including means for retaining a portion of said pin, said retaining means comprising a groove in said plate for releasably receiving at least one end of said pin, said groove being generally V-shaped and being defined by a generally vertical edge which acts as a stop for an end of said pin and a generally sloping edge for camming said end of said pin into and out of said groove.

10 15 3. An orthodontic bracket as claimed in claim 2 wherein said pin is threadedly engaged in said tube passage and said pin is rotatable from a position whereby said portion thereof extends toward said plate to a position whereby said portion thereof extends substantially parallel to said plate.

4. An orthodontic bracket as claimed in claim 2 wherein said pin has the general configuration of an inverted J with the long leg thereof extending through said tube passage and the short leg thereof received by said retaining means, the outer end of said long leg behind bendable out of alignment with the longitudinal axis of said passage for retaining said pin in said tube.
